UNITED STATES PATENT OFFICE.

RALPH W. CLAYBAUGH, OF PACIFIC GROVE, AND GEORGE D. PATRICK, OF MONTEREY, CALIFORNIA, ASSIGNORS OF ONE-THIRD TO VICTOR H. PATRICK, OF MONTEREY, CALIFORNIA.

AIR HEATING AND CIRCULATING FIREPLACE.

Application filed February 29, 1928. Serial No. 258,117.

This invention relates to air-heating-and-circulating fireplaces, the principal object of which is to provide a fireplace wherein, all but a small percentage of the heat generated in the firebox is applied to induce a circulation of heated air within certain air spaces and ducts, all in intercommunication with a related distributive system for the utilization of said heated product.

10 Another object is to provide as a new article of manufacture, a fireplace that may be installed intact ready for use in buildings already constructed.

15 Another object is to provide certain interrelated air ducts adapted to absorb heat from a chimney and firebox back.

A still further object is to provide an air space around said firebox within a mantel, said space communicating with said ducts.

20 Another object is to provide certain perforate air passages for the ingress of cold air and egress of said heated product.

A further object is to provide a series of nested wall-ducts having crimped, folding, 25 spacing and stiffening means adapted to absorb heat.

Another object is to provide a manifold means interrelated with ingress elements and with a system of distribution for said product.

30 A still further object is the provision of certain regulative damper means.

Another, is the provision of a hollow door having perforate means for cold air intake 35 and hot air egress.

A further provision comprises regulative means for raising and lowering said door.

Further provisions comprise baffle element adapted to absorb heat.

40 Still further provisions are comprised in certain peculiar fastening means whereby the chimney element is united to the fireplace-mantel element.

These objects are attained generally by the 45 form, material and construction of the parts employed, together with other objects and advantages that will hereinafter appear.

In the drawings.—

Figure 1 is a front elevation of our invention.

Fig. 2 is a sectional elevation on line I—I of Fig. 1.

Fig. 3 is a section on the line II—II of Fig. 1.

Fig. 4 is a plan.

Fig. 5 is a section on the line III—III of Fig. 4.

Fig. 6 is a detail view of the elements composing Fig. 7.

Fig. 7 shows a broken view of the elements 60 of Fig. 6 united.

Fig. 8 is a broken view of an air duct element.

Like reference characters refer to like parts 65 throughout the several views.

Referring in detail to the drawings, Figure 1 illustrates a fireplace according to our invention, having a conventional brick base 2, the mantel front 3 and the ends thereof 3^a and 3^b with the mantel shelf 4. Spaced with- 70 in said mantel and equidistantly from the interior of said front and ends is the firebox denoted 100 as a whole, which comprises the bottom 5, the respective ends 6 and 6^a and the front 7.

Both the mantel front 3 and the firebox front 7 are provided with coincident door- 75 openings the edges of which are beaded over at 9 and 9^a suitably spaced apart so as to provide vertical guides for the door 8 to play up and down in. Said door is of double construction having the members 8^a and 8^b one behind the other, the lower front of member 8^a being provided with the perforations 10 while the upper portion of said door is pro- 80 vided with the perforations 11 which allow air to ascend into the prismoidal space 12 that communicates at each end thereof with the spaces 13 and 14 existing between the outer ends 6 and 6^a of the firebox 100 and the 85 interior of the mantel.

The door 8 is provided adjacent the inner upper corners with the lugs 15 and the flexible means 16 attached thereto which pass over the pulleys 17 and attach to the counter-balance 90 weights 18 which constitute a means of regulating the height of said door for direct admittance of air to said firebox through said door openings.

Underneath the hearth member 19 of the 100 firebox 100 is the space 20 existing between the under surface of said hearth 19 and the upper surface of the brick base 2 said space being guarded by the reticulated means 21 at the lower front of said mantel 3, it being un- 105 derstood that said mantel stands on the four feet 22, 23, 24 and 25 which rest on the brick-work 2.

The mantel-ends 3^a and 3^b are both provided with suitable perforate means 26 adapted to admit air to the space 20. The front of said mantel may have its flat surface relieved by a suitable embossed panel as 27.

The back of the fireplace 100 is bounded by the flat plate 28 which is secured to the back edge of the hearth-member 19 with the lower end of said plate flush with said hearth there-
10 by continuing the space 20 from the front and both sides backwardly underneath the hearth 19 and up behind the plate 28. From the level of said hearth the plate 28 rises upwardly for a suitable distance and is then in-
15 clined forwardly at an approximate rising angle of 30 degrees, whence it is inclined backwardly at an approximate rising angle of 45 degrees, thereby forming the V-shaped projection of said firebox which by co-oper-
20 ating with the opposing parallel surface of the V-shaped projection 30 restricts the flue area. The upper end of the plate 28 termi-
25 nates in the folded groove-like member 31 adapted to sheath the bottom of another sheet, to be described, and disposed vertically thereto. Disposed behind the sheet 28 and suitably spaced apart are the parallel sheets 28^a and 28^b, which sheets may obviously be increased or diminished in number, said sheets
30 being provided with the spacing stiffening elements 32 preferably formed by crimping or plaiting the stock together, in the manner shown in Figs. 3 and 8, so as to form a series of longitudinal ribs, the rounded ridges 33
35 of which are adapted to mate with the counterpart seams 34 of the opposing sheet, said sheets having their ends level with that of sheet 28.

The hindmost sheet 36 does not communicate with the circulation system as do the others. All of the said sheets being provided with suitable flanges as 37, 38 and 39 which are adapted to nest one within the other and within the mantel ends 3^a and 3^b 45 to which they are secured by the through bolts 39. The perforations 40 being provided to allow air to enter behind the sheet 36 to cool the wall 41.

The upper edges of the mantel may either 50 be left as a section of the stock, be curled over inwardly as shown at 42, Fig. 2 or provided with other suitable finish means.

The upper edges of the firebox however are provided with trough-like elements 43 55 adapted to accommodate the complement member 43^a as shown in the complement units of Fig. 6 and as assembled in Fig. 7.

The foregoing relates exclusively to the parts and elements comprised in our invention approximately below the line IV—IV of Figs. 1 and 2, which may or may not be constructed as a separate unit.

We will now describe the chimney and distributing system for the air product.

65 The chimney proper is a metallic shell of

tapering structure comprising the receding front 44 and the ends 45 and 45^a, the latter being united to the plate 46 by welding or in other suitable manner.

Adjacent the mantel-shelf 47 the tapering structure composed of the parts 44, 45 and 45^a gives place to the vertical walls 44^b, 45^b and 45^c which in turn terminate in the element 43^a which is adapted to fit into its trough 43 being secured thereto by bolt means as 48. 75

Disposed at a suitable level within said chimney, and by preference at the left hand side thereof, is the damper means 50, pivoted at 51 to the bracket 52 which is attached to the inner side of the chimney; while, diametrically opposite said damper, the offset member 54 is securely attached by the bottom end thereof to the plate 46 by the rivet means 55, said member extending thence in an upward direction, (preferably at the same angle as that of the chimney-front 44) and terminating at the top of the chimney shell.

Now, as said chimney top is oblong the oblong fitting 56 is provided as a finial, said fitting having the downwardly-extending flanges 57 adapted to fit said top and which may be hammered back to the internal taper of the chimney-top to lock said fitting securely in place, and having an upwardly disposed flange 58 adapted to accommodate the terra-cotta pipe 59 when socketed therein. Above said flange, resting with its bottom member 60 on the top of the former, is the casing flange 61.

The member 60 is disposed in a suitable "well" approximately located in a ceiling and depends therefrom by the rim 62 supported on the "well" timbers, when thus installed said member 61 forms an appropriate support for a ventilating casing which may extend upward for any required distance, and will pass rigid underwriter inspection. 105

The manifold may be provided with either one or a plurality of distributing conduits as 64, 65 and 66 which may in turn be provided with the usual register outlets, 67. Said manifold is provided with the folded groove 68 extending all round it and adapted to fit closely down on the top ends of all the associated plates. 110

At 69—69 is shown a grid-work disposed in front of the registers 70—70 which are pivoted at 71 and adapted to swing in the direction indicated by the dotted lines associated therewith in Fig. 2. 115

The handles 72 and 73 show conventional means of adjustment of the damper 50 and the register elements 70. It is believed that from the foregoing it will be clear that we prefer to manufacture our apparatus in two 125 separate units that may be readily assembled in the following manner:

The mantel firebox element is first set up in place on the brickwork foundation 2; next, plastic asbestos cement is filled into all joints 130

such as the trough element 43, the fold 31 and other parts and places where air would be liable to leak. The chimney element is next put in place seeing that all the various joints agree. Then the bolts 48 of which one only is illustrated are inserted and put through their registering holes in the element 43 thus binding the chimney unit to the mantel fire-box unit. Next the mantel-shelf 47 is put on by means of the bolts 47^a. Nothing remains to be done now but set the manifold 63 in position and connect the various conduits.

It is believed that the construction, operation and advantages of the invention will now be clearly understood. The present embodiments of the invention have been disclosed in detail merely by way of example, since in actual practice they attain the features of advantage set forth as being desirable in the statement of the invention and the above description.

Numerous changes in the details of construction, and in the combination and arrangement of parts may be resorted to without departing from the spirit or scope of the invention as hereinafter claimed or sacrificing any of its advantages.

Having thus described our invention, what we claim as new is:—

- 30 1. A heater unit for fire places adapted for insertion in the lower portion of the chimney cavity between the mantel and the back wall of said cavity, said unit consisting of an oblong, upstanding casing comprising closed end and back walls, closed base plate and open top and front, a fire box located inside said casing, an air chamber below said fire box, air conduits at the ends of said casing, and a series of air flues at the back of the fire box 40 in communication with the bottom air chamber, and an air chamber at the front of said casing in communication with the bottom, rear and end air circulating systems.
- 40 2. A heating unit according to claim 1, in which the front and rear walls of the fire box

are bent to form a contracted flue, of zigzag shape, communicating with a chimney flue.

3. A heating unit adapted to be constructed in complete form for insertion in a fire place, and comprising the elements recited in claim 1, the front wall of said unit, and the front wall of the fire box being formed with coincident openings for access to the fire space, and provided with a vertically sliding door located between the two walls.

4. A heating unit adapted to be constructed in complete form for insertion as a whole, into a fire place consisting of a main casing, comprising end walls, a back wall, and a front wall, and vertical partitions producing a fire box, separated at the ends and sides from the main casing and providing separate air flues at the ends, rear and front walls of the casing, with an air space below the floor of the fire box having openings in its walls for the admission of fresh air from the end flues, said lower air space being in communication leading upwardly from the rear of the casing, back of the fire box to the distributing flues.

5. A heater of the character described, and specifically claimed in claim 1, in combination with a superposed chimney unit, constructed with a hot air flue section in the rear of its back wall communicating with a similar flue back of the fire box of the lower unit.

6. A heater of the character described, comprising a unit adapted to be inserted in a fire place encased by a mantel, and consisting essentially of a fire box, an enclosing casing and partitioned vertical flue and a superposed vertically independent chimney unit communicating with the fire space of the lower unit and constructed and adapted to communicate heat to a series of air flues located in the rear thereof.

In testimony that we claim the foregoing as our own, we have hereunto affixed our signatures this 17th day of February, 1928.

RALPH W. CLAYBAUGH.
GEORGE D. PATRICK.
